SLIVER-BALLING MACHINE

Application filed September 20, 1929, Serial No. 394,107, and in Great Britain February 28, 1929.

This invention relates to machines contrived to form rolls or balls of sliver or the like upon a sectional arbor located between a pair of rotatable discs, being concerned 5 more particularly with machines for making and ejecting automatically rolls of sliver delivered continuously from a carding engine or drawing frame or other machine which delivers fibre in sliver or ribbon 10 form.

For convenience we shall describe in detail a machine adapted for handling the sliver from a carding engine or drawing frame.

15 Solid with two separable coaxial discs are horizontal arbor-sections to which sliver is delivered from the usual delivery rollers of the carding engine or drawing frame. Adapted to be accommodated between the 20 discs is a fluted roller driven at a surface speed which may be a small percentage faster than that of the delivery rollers. The discs and therewith the arbor-sections are carried by arms pivoted to a sleeve or the 25 like loosely mounted on a horizontal shaft, the arms rising with the formation of the roll of sliver, until, when the roll attains a predetermined size, or a predetermined length of sliver has been delivered, means 30 is actuated to swing the arms apart to effect the separation or "opening" movement of the discs with the arbor sections and thus leave the roll of sliver free to be ejected.

To break the sliver after ejection of the 35 roll, the sliver from the finished roll is nipped between the arbor-sections which are moved towards one another or "closed" after ejection of the roll, it being understood that, on continued rotation of the arbor-sections, sliver will be pulled in the direction 40 away from the finished roll so that a break is effected between the finished roll and the point of nip between the arbor sections.

At the start of a new roll the rim of either 45 or each disc is in contact with a friction

wheel driven at such a speed as to rotate the disc at a speed above normal so that the arbor-sections will immediately acquire a speed approximating that of the sliver being delivered. At the commencement of rotation the arbor-sections are held clear of contact with the fluted roller by the disc rims engaging the friction wheels until there are sufficient turns of sliver wound on the arbor-sections to make contact with the 50 fluted roller by which the arbor-sections are lifted together with the discs, so that the disc rims leave the friction wheels and the arbor-sections with the discs are then driven by the fluted roller acting frictionally on 55 the wound sliver.

When the roll has been completed and ejected the discs are returned to initial or "closed" position, their fall being cushioned by a hydraulic control device so that the 60 rims of the discs will come to bear gently on the friction wheels.

A machine constructed in accordance with the invention is illustrated in the accompanying drawings in which Fig. 1 is a part 70 elevation part vertical section; Fig. 2 is a part plan part section; Fig. 3 a horizontal section substantially on the line 3—3 of Fig. 1; Figs. 4 and 5 are diagrammatic views illustrating progressive stages in the operation 75 of the machine; Fig. 6 is a fragmentary part elevation part section showing the disc "opening" and "closing" mechanism; Figs. 7 and 8, are, respectively, a vertical section and a plan view of a hydraulic control device; Fig. 80 9 is a fragmentary detail view showing mechanism associated with the hydraulic control device; Fig. 10 is a fragmentary view of manual ejecting mechanism; Fig. 11 is a diagram showing one form of means to receive the 85 roll after ejection.

The machine shown comprises a pair of axially spaced discs 1 solid with arbor sections 2 revoluble on ball bearings 3 mounted on pins 4 carried on the free ends of a pair 90

of arms 5 whose opposite ends are bifurcated and pivoted at 6 to a sleeve 7 loosely mounted on a stationary horizontal shaft 8 sustained by spaced gable frames 9, 9', the arrangement being such that the discs 1 are movable together circularly about the axis of the shaft 8 and, in addition, the arms 5 are free to swing on the pivots 6 whereby the discs may be moved apart or "opened" to permit ejection of a roll of sliver. Disposed beneath and between the discs 1 is a fluted roller 10 secured to a shaft 11 journalled in the frames 9, 9' and carrying at one end, projecting beyond the frame 9, a gear wheel 12 meshing with a gear wheel 13 journalled on a pin 14 carried by the frame 9. The gear wheel 13 is unitary with a gear wheel 15 meshing with a gear wheel 16 solid with sprocket wheels 17, 18 and journalled on a pin 19 carried by the frame 9. The sprocket wheel 18 is wrapped by a chain (not shown) driven from any convenient rotating shaft of the carding engine or drawing frame. The sprocket wheel 17 is wrapped by a chain 20 which also wraps a sprocket wheel 21 secured to a shaft 22 journalled in the frame 9, 9' and carrying a pair of friction wheels 23 axially spaced on the shaft 22. The face width of the fluted roller 10 is such that the roller can enter the gap between the discs 1 when the discs are in lowered position and the friction wheels are so positioned on the shaft 22 that, when the discs 1 are in their lowermost position, the peripheries of said wheels engage the rims 1' of the discs 1. Above the discs 1 are the delivery rollers 24, 25 adapted to deliver sliver 26 between the discs 1.

The means for effecting angular movement of the arms 5 about their pivots 6 comprises axially spaced flange members 27 (of which one is shown in Fig. 6) revolvably mounted on a stud 28 carried by the sleeve 7.

Interposed between the flange members 27 and pivoted thereto at 29 are two curved links 30 the ends of which remote from the pivots 29 are pivoted at 31 to members 32 pivoted at 33 to the arms 5. 30' denotes stopper pins carried by the members 27 and engageable by the links 30 in the "closed" position of the discs 1. Carried by the members 27 is a roller 27' engageable by a blade spring 27" carried by the sleeve 7 so as to locate the members 27 in their "dead centre" position, i. e., the positions in which the discs 1 are "open" and the position in which they are coaxial or "closed."

Pivoted at 34 to the members 27 is a member 35 (Figs. 1 and 5) to which is pivoted at 36 the upper end of a lengthwise adjustable link 37 of which the lower end is pivoted at 38 to a member 38' pivoted at 38" to an arm 39 loosely mounted on a shaft 41 extending between the frames 9, 9' and journalled therein. 42 denotes an arm integral

with the arm 39 and engageable by the upper end of a tappet rod 43 guided in lugs 44 integral with a depending lever 45 of which the upper end is pivoted at 46 to an arm 47 integral with the sleeve 7. Solid with the tappet rod 43 is a follower 48 of which the under face 49 is engageable by a cam 50 carried by the shaft 11. 51 denotes a lever adjustably pivoted at 52 and engaging a second cam 53 secured to the shaft 11. Carried by the lever 45 is an adjustable set-pin 54 of which the head 55 is engageable by a third cam 56 secured to the shaft 11. Urging the lower end of the lever 45 toward the shaft 11 and attached at 57 to the lower end of the lever 45 is one end of a helical tension spring 58 of which the other end is anchored at 59. The spring 58 serves normally to maintain an edge 60 presented by the lever 45 in engagement with a pin 61 carried by the lever 51, said edge 60 presenting a step 62 engageable by the pin 61 as hereinafter explained.

Solid with the sleeve 7 is an arm 63 to which is pivoted at 64 the upper end of a link 65 of which the lower end is operatively connected to a hydraulic control device including a piston 66 movable horizontally in a cylinder 67 secured to the frame 9'. Formed in the piston 66, intermediate the ends thereof, is a notch 62 engaged by a toe 69 on one arm 70 of a bell-crank lever fulcrumed at 71. The lower end of the link 65 is pivotally connected at 72 to the other arm 73 of the bell-crank lever. A chamber 66' at one end of the cylinder 67 is controllable by a valve 74 operatively connected at 75 to one arm of a cruciform lever 76 pivoted at 77 and urged by a helical compression spring 78 in the direction to maintain the valve 74 open, the extent of valve opening being determined by the setting of a set screw 79 carried by the cruciform lever and normally engaging an abutment 80. A chamber 66" at the other end of the cylinder 67 is controlled by a valve 81 cooperating with an aperture 81' and operatively connected to a valve spindle 82. Interposed between a nut 83 screw-threaded on the upper end of the valve 81 and adjustable nuts 82' on the spindle 82 is a helical compression spring 84 serving normally to maintain the nut 83 in engagement with a collar 85 on the lower end of the spindle 82 (Fig. 9). Surmounting the cylinder 67 is a fluid reservoir 86 which communicates with the chambers 66', 66" under the control of the valves 74 and 81.

Pivottally connected at 87 to the lever 76 is the lower end of a link 88 guided through an eye 89 secured to an arm 90 secured to the shaft 41. 92 denotes a helical compression spring surrounding the link 88 and interposed between the eye 89 and nuts 93 threaded on the link 88 near the upper end thereof.

The upper end of the valve spindle 82 has

a pin-and-slot connection 94 (Fig. 9) with a lever 95 pivoted at 96 at one end and urged upwardly by a tension spring 97 at the other end. Pivoted at 98 above the lever 95 is 5 a bell-crank lever of which the arm 99 is engageable with a cam 100 formed on the lever 95 and of which the arm 101 is engageable by a set-screw 102. The said set screw is carried by a bracket 103 secured to the link 105. The lever arm 99 is also engageable by 10 a pin 104 carried by a bracket 105 secured to the lever 45. The arm 101 presents an eye 107 penetrated by a rod 108 between a collar 109 on the lower end of which and the eye 107 is interposed a compression spring 110. The upper end of the rod 108 is pivotally 15 connected at 111 to a curved lever 112 pivoted at 113 and formed at its outer end with a notch 114 normally in latching engagement 20 with a member 115 carried by a curved lever 116 secured to the shaft 41. Secured also to the shaft 41 is a bracket presenting arms 117, 118 having lateral projections 117', 118', respectively, engageable, respectively, with 25 the arm 39 and with an arm 120 loose on the shaft 41 and carrying an adjustable set-screw 119 engageable with the arm 39. The arm 120 is movable normally with an arm 121 loose 30 on the shaft 41 and operatively connected by means of a link 102 to the arm 63 on the sleeve 7. The arm 121 carries a latch 123 operatively connected to the curved lever 112 by means of a link 124 and normally in latching 35 engagement with the arm 120.

In operation, at the commencement of a roll-forming operation, the discs 1 are in lowered position (as shown in Figs. 1 and 4) with their rims 1' frictionally engaging the friction wheels 23 which impart rotation to the discs in the direction indicated by the arrow A. When entrainment of the sliver 26 by the rotating arbor-sections 2 is effected, wrapping of the sliver upon the arbor-sections commences. In the building of the roll, after the first few turns of sliver are wrapped upon the arbor-sections, the sliver is engaged by the fluted periphery of the roller 10 which is rotating in the direction indicated by the arrow B, whereby the discs are raised clear of the friction wheels 23, the roller 10 effecting further rotation of the arbor sections 2 and discs 1. As the diameter of the roll increases, the discs 1 and therewith the levers 5 and 45 rise until, at a point when the 45 roll has attained a predetermined diameter and when the edge 60 of the lever 45 is disengaged from the pin 61 carried by the lever 51, the step 62 on the lever 45 is latched into engagement with the pin 61 by the action of the spring 58 (as shown in Fig. 5). When 50 now the lever 51 is raised by the cam 53, the lever 45 and therewith the discs 1 are slightly raised so that the roller 10 is relieved of load. In the raised position of the lever 45 the upper end of the tappet-rod 43 carried

thereby is located adjacent to the arm 42 and the member 48 on the tappet-rod 43 is disposed in the path of the cam 50 as shown in Fig. 5. While the discs 1 are still sustained by the cam 53, the cam 50 engages the face 49 of the member 48 and impels the tappet-rod 43 upwardly into engagement with the arm 42 which is thereupon rocked and, through the intermediary of the train 39-34, rotates the members 27 in the direction indicated by the arrow C (Fig. 6) whereby the links 30 are operated to separate the arms 5 and therewith the discs 1 and arbor-sections 2. The sliver roll, being now released, drops into contact with the roller 10 which assists in ejecting the rolls S on to revolving rollers 125, 126 (Fig. 11) operatively interconnected by a chain 127 and driven at a peripheral speed equal to that of the ejected roll. The roll S may be lifted from the rollers 125, 126 by hand or the roller 126 may be axially inclined relatively to the other roller 125 so as finally to cant the roll S over one end of the rollers. During the rise of the discs 1 the piston 66 is moved in the direction indicated by the arrow D (Fig. 7) through the intermediary of the train 69, 70, 73, 65, 64, 63 whereby fluid pressure is built up in the chamber 66² to oppose rising movement of the discs 1 so as to supply the requisite pressure between the sliver roll and the roller 10 to compact the sliver. 55

During this rise of the discs 1 the lower end of the arm 99 (Fig. 9) is in engagement with the upper edge of the cam 100 on the lever 95 whereby said lever is depressed in opposition to the action of the spring 97, the valve 81 being thus closed or practically closed. As the piston 66 advances into the chamber 66², fluid leaks slowly from the chamber 66² past the valve 81 into the reservoir 86. It will readily be understood that the degree of pressure built up within the chamber 66² during the rise of the discs 1 and consequently the density of the sliver roll is determined by the stress of the spring 84 which is regulatable by adjustment of the nuts 82'. The valve 81 thus also acts as a safety release valve to prevent abnormal rise of pressure within the chamber 66². 105 While pressure is being built-up within the chamber 66², fluid flows from the reservoir 86 into the chamber 66² by way of an aperture 74' which presents a seating for the valve 74. When the step 62 on the lever 45 is 110 latched into engagement with the pin 61 at the completion of the roll, the pin 104 trips the arm 99 (Fig. 9) out of engagement with the cam 100 on the lever 95 whereby said lever 95 is raised by the spring 97 to open the valve 81 and relieve the pressure in the chamber 66². 115

After ejection of the roll, in the continued rotation of the shaft 11, the cam 56 engages the head 55 of the set-pin 54 whereby to repel 120

the lever 45 and disengage the step 62 from the pin 61, whereupon the discs 1 commence to descend and the edge 60 of the lever 45 re-engages the pin 61. The piston 68 now moves in the opposite direction, the resistance offered thereto cushioning the descent of the discs, the fluid in the chamber 66' escaping to the reservoir 86 by way of the valve-controlled aperture 74'. Adjustment of the set screw 79 to vary the extent of opening of the valve 74 permits regulation of the speed of descent of the discs 1. As the piston 68 vacates the chamber 66', fluid from the reservoir 86 is drawn into said chamber by way of the aperture 81'.

When the cam 50 releases the member 48, said member and therewith the tappet rod 43 will drop by gravity into position, it being understood that, when the member 48 is released, the edge 60 of the lever 45 is in engagement with the pin 61.

A slight dwell is provided between the operation of the cams 50 and 56 so as to permit ejection of the roll before the lever 45 is tripped. About midway in the descent of the discs the set-screw 119 carried by the arm 120 which, during the descent of the discs, has been moving upwardly to meet the downwardly moving arm 39, engages said arm 39 whereby to rotate the members 27 so as to operate the links 30 to move the discs 1 towards one another. When the arbor-sections come together, the sliver is entrained and severed between the contiguous faces of the arbor-sections 2 and, when the discs again engage the friction wheels 23, the formation of a new roll commences. It will be understood that, when a roll is ejected on to the rollers 125, 126, the sliver extending from the delivery rollers 24, 25 to the ejected roll lies in a path such that, when the discs are closed, the sliver is engageable by the arbor-sections 2. In the descent of the discs, just before they engage the friction wheels 23, the set-screw 102 (Fig. 9) moving with the link 65 engages the arm 101 whereby to move the arm 99 into engagement with the cam 100 and close the valve 81, it being understood that, in this position of the discs, the pin 104 is clear of the arm 99.

To effect ejection of a partially formed roll, the lever 112 is raised to unlatch the lever 116 whereupon the latch 123 is unlatched from the arm 120 which drops into engagement with the projection 118' on the arm 118. The upward movement of the lever 112 also causes the arm 99 to disengage the cam 100, whereupon the valve 84 is opened under the action of the spring 97. The lever 116, being now freed, is pushed forwardly, whereby the projection 117' on the arm 117 is caused to engage and to depress the arm 39 to effect movement of the discs apart to permit ejection of the partially formed roll. When the lever 16 is pushed forwardly, the

valve 74 is closed through the intermediary of the link 88, whereby to prevent descent of the discs. It will be seen that, when the arm 120 is released from the arm 121, the arm 120 permits depression of the arm 39 by the arm 117. Reverse movement of the lever 116 raises the arm 118, 120 and brings the set-screw 119 into engagement with the arm 39 so as to rock said arm 39 to effect movement of the discs 1 towards one another. When the lever 112 is moved to latch the lever 116, the latch 123 again latches the arm 120 to the arm 121. Reverse movement of the lever 116 also reopens the valve 74 so that the discs 1 commence to descend. In the descent of the discs, just before they engage the friction wheels 23, the set screw 102 engages the arm 101 of the bell-crank lever 99, 101 whereby to rock said lever to close the valve 81 ready for a restart.

We claim:—

1. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve rockable about an axis parallel with said common axis, two arms pivoted to said sleeve on axes transverse to the axis of said sleeve, and means sustained by said sleeve and operative on completion of a ball to swing said arms apart and thereby to swing said discs each with its arbor section bodily apart to free the ball.

2. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve rockable about an axis parallel with said common axis, two arms pivoted to said sleeve on axes transverse to the axis of said sleeve, friction means engaging the ball of sliver being formed for rotating said discs and arbor sections, and means rotating with said friction means operative to cause said arms to be swung apart to permit ejection of the ball by said friction means.

3. In a machine for forming rolls of sliver or the like, in combination, two-spaced discs revoluble on a common horizontal axis, complementary arbor sections solid with said disc, a shaft parallel with said axis, a sleeve loose on said shaft, arms each pivoted at one end to said sleeve on an axis transverse to that of said sleeve and carrying at the opposite end a disc and arbor section, and a rotary member linked to said arms and operative to

swing said arms apart on their pivots to permit ejection of the sliver roll.

4. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said sleeve, pins, one at the free end of each arm, affording journals for said discs, and means sustained by said sleeve and operative on completion of a ball to swing said arms apart and thereby to swing said discs each with its arbor section bodily apart to free the ball.

5. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said sleeve, pins, one at the free end of each arm, affording journals for said discs, means sustained by said sleeve and operative on completion of a ball to swing said arms apart and thereby to swing said discs each with its arbor section bodily apart to permit ejection of the ball, and means for loading the discs and arbor sections during formation of the ball and for cushioning the return movement of said arms, discs and arbor sections after ejection of the ball.

6. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said sleeve, pins, one at the free end of each arm, affording journals for said discs, a cam rotatable with said roller, and means, influenced by said cam and operatively connected with said arms, for swinging said arms apart and thereby swinging said discs each with its arbor section bodily apart to free the ball.

7. A sliver balling machine comprising, in combination, two spaced discs each solid with an arbor section, said discs being located during the ball-forming operation on a common axis with said arbor sections in abutting relation, a roller engageable with

sliver being wound on said sections, a sleeve parallel with said common axis, two arms pivoted to said sleeve on axes transverse to the axis of said sleeve, journal members for said discs, said members being sustained by said arms, a train of interconnected members operative on completion of a ball to swing said arms apart and thereby to swing said discs each with its shaft section bodily apart to free said ball, said train including a manually operable member, and a manually releasable latch co-operative with said manually operable member.

8. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said sleeve, pins, one at the free end of each arm, affording journals for said discs, a controlling disc carried by said sleeve, levers connected to spaced points of said controlling disc and to said arms, and means operative on completion of a ball to rock said controlling disc and thereby to swing said arms apart.

9. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said sleeve, pins, one at the free end of each arm, affording journals for said discs, a controlling disc carried by said sleeve, levers connected to spaced points of said controlling disc and to said arms, a cam rotatable with said roller, a tappet rod actuated by said cam, a bell-crank lever influenced by said tappet rod and a tension rod connected to said bell crank lever and operatively connected to said controlling disc for imparting turning movement to said controlling disc whereby to swing said arms apart.

10. A sliver balling machine comprising, in combination, two spaced discs each solid with an arbor section, said discs being located during the ball-forming operation on a common axis with said arbor sections in abutting relation, a roller engageable with sliver being wound on said arbor sections to impart rotary movement to said discs and arbor sections, a sleeve parallel with said common axis, two arms pivoted to said sleeve on axes transverse to the axis of said

sleeve, pins, one at the free end of each arm, affording journals for said discs, a cam rotatable with said roller, means influenced by said cam to lift said arms slightly to relieve the ball of pressure, a second cam rotatable with said roller, and means, influenced by said second cam and operatively connected with said arms, for swinging said arms apart and thereby swinging said discs each with its arbor section bodily apart to free said ball.

In testimony whereof we have signed our names to this specification.
